ATTORNEY

UNITED STATES PATENT OFFICE

WILLIAM H. SCHLESINGER, OF BROOKLYN, NEW YORK

DESIGN FOR A LAMP

Application filed March 4, 1931. Serial No. 38,920. Term of patent 3½ years.

To all whom it may concern:

Be it known that I, WILLIAM H. SCHLESINGER, a citizen of the United States, residing in Brooklyn, county of Kings, and State of New York, have invented a new, original, and ornamental Design for a Lamp, of which the following is a specification, reference being had to the accompanying drawing, forming part thereof.

Fig. 1 is a front side elevation.

Fig. 2 is a rear side elevation.

Fig. 3 is a front end elevation.

I claim:

The ornamental design for a lamp, as shown.

WILLIAM H. SCHLESINGER.
